UNITED STATES PATENT OFFICE

ADOLPH G. LOTTER, OF MILWAUKEE, WISCONSIN, ASSIGNOR TO STATIONERS LOOSE LEAF CO., OF MILWAUKEE, WISCONSIN, A CORPORATION OF WISCONSIN

LOOSE LEAF BINDER

Application filed December 7, 1929. Serial No. 412,343.

This invention relates to certain new and useful improvements in binders particularly of the type used to protect important records such as kept by the offices of registers of deeds and which usually have a large body of leaves secured between cover members by posts passed through the leaves and detachably connected with the cover members.

The over-all size and weight of binders of this general type makes them rather awkward and difficult to handle, especially in removing leaves from the binder, when it has been necessary to, with one hand, pull the open cover out of the way of the posts while the other hand is used to remove the leaves.

This invention, therefore, contemplates as one of its objects the provision of structural means whereby, when the post-securing means is released and the cover swung open, the cover will move free of the binding posts and remain in this position so that the leaves may be assembled and removed with ease.

A more specific object of this invention resides in the provision of a reinforcing plate secured to the hinge plate of each cover and extending to a point close to the inner edge thereof whereby the binding cloth forming a portion of the flexible hinge between the back member and the cover is held close to the plate outer edge at all times so that the weight of the cover swings the back member away from the body of leaves as it is swung open and the binding post securing means is released.

With the above and other objects in view which will appear as the description proceeds, my invention resides in the novel construction, combination and arrangement of parts substantially as hereinafter described and more particularly defined by the appended claims, it being understood that such changes in the precise embodiment of the here-in-disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a fragmentary perspective view illustrating the position assumed by the conventional type of binder of the character described when the cover is swung open and the binding post securing means unlocked; 55

Figure 2 is a view similar to Figure 1 illustrating the position assumed by the device of this application under similar conditions, and

Figure 3 is an enlarged, fragmentary perspective view taken on the plane of the line 3—3 of Figure 2 and having parts broken away and in section to illustrate structural details.

Referring now more particularly to the accompanying drawings, 5 and 6 represent the cover members and 7 the back piece of a binder of the character described. The cover members are adapted to be flexibly connected with the side marginal edges of the back piece 65 by means of a flexible binding strip 8 secured to the inner surface of the back piece and having its side marginal edge portions confined between the bottoms of recesses 9 in the cover members, and metal plates 10. 70

The plates 10 project beyond the inner marginal edges of the cover members and are folded longitudinally, as at 11, and recessed, as at 12, to provide openings in which the adjacent ends 13 of binder posts 14 are received to be pivotally connected with the plates by locking means 15 of the general type illustrated in Letters Patent No. 1,713,544 issued Henry C. Miller the 21st day of May, 1929. 75

An outer binding or covering 16 which may be leather or other suitable material cooperates with the material 8 to form the hinges for the covers.

In binders of this character, it has been customary to glue the fabric 8 to the inturned portion 11 of the metal plate 10 so that the fold 17 thereof is at a point near the outermost edge of the plate, but with the first opening of the cover the fabric 8 becomes detached from the plate 10 so that the point of hinging is virtually at the inner marginal edge of the cover. This is undesirable for when the locking mechanism 15 is manipu- 90
95
100

lated to release the binder posts and the cover opened, the parts assume the positions illustrated in Figure 1, due to the weight of the body of leaves 18 causing the back piece to remain in a substantially vertical position, the cover having its extreme outermost edge resting on the support or desk on which the binder is resting.

With the binder parts in this position, the removal of the leaves as a body or any portion thereof necessitates that the operator grasp the topmost cover with one hand and force it to the left with reference to Figure 1, and with the other hand endeavor to remove the leaves, an extremely awkward operation and frequently resulting in tearing of the leaves.

This objectionable feature is overcome by providing a novel hinge structure between each cover and the back member, and as the structure at both covers is identical the single detail illustration in Figure 3 is deemed sufficient for a proper disclosure of the invention. As here shown a metal plate or reinforcing member 19 is secured in the recess 9 of each cover between the adjacent portion 20 of the fabric 8 and the bottom of the recess with its outer marginal edge extended beyond the cover and over the folded edge 11 of the plate 10 to hold the fabric 8 in engagement therewith, so that the point of pivotal connection between each cover and the back piece is nearer the inner edge of the fold 11. The reinforcing members 19 not only shift the line of effective hinge toward the inner end of the fold 11, but in doing so also limit the opening movement of the covers with respect to the back member. Hence when the book is open and the connection between the upper cover and the post members released, the hinge connection between the upper cover and the back member, after the limit of relative movement between these elements is reached, serves to rigidly connect the same so that the weight of the cover causes the back to assume the position illustrated in Figure 2 free of the binding post ends 13 permitting any one or all of the leaves to be removed with ease and facility. The weight of the cover is sufficient to lift the leaves the slight distance incidental to the movement of the back to the position shown in Figure 2, in that the cover and the back member together form a lever the fulcrum of which, being provided by the curved portion of the back member, is near the weight to be lifted, namely the body of leaves, with the applied weight, which is provided by the outer portion of the cover, spaced considerably from the fulcrum.

From the foregoing description, taken in connection with the accompanying drawing, it will be readily apparent to those skilled in the art to which an invention of the character described appertains, that I provide novel means for facilitating the removal or inser-

tion of leaves of large record binders without danger of tearing the same.

What I claim as my invention is:

1. A loose leaf binder comprising a back member, a cover, a hinge plate secured to the cover, a binder post, means pivotally and removably connecting the binder post with the hinge plate of the cover, flexible means connecting the cover with the back member, and a second plate cooperating with the hinge plate to secure said flexible means longitudinally along the hinge plate at a point close to the inner marginal edge thereof and to limit movement of the cover in one direction with respect to the back member. 70 75

2. A loose leaf binder comprising a pair of covers, a back member, a flexible covering for the back member extended therebeyond and secured to the cover members to provide a hinge connection therebetween, a plate member carried by each cover member, binder posts, releasable means pivotally connecting the ends of the binder posts with the hinge plates of the cover members, and a reinforcing plate confining said flexible connection between it and the inner surface of each hinge plate and terminating close to the inner end of said hinge plate, whereby the point of pivot of said cover with respect to the back member is such that the hinge plate is carried away from the binding post when swung to open position and the pivotal connecting means released. 80 85 90 95

3. In a binder of the character described, having a back and covers hingedly connected therewith, post members, releasable means pivotally connecting the post members with the covers, and means for limiting opening movement of the covers with respect to the back, whereby the weight of the uppermost cover in open position and disconnected from the post members swings the back away from the post members to facilitate removal and insertion of leaves. 100 105 110

In testimony whereof I have hereunto affixed my signature.

ADOLPH G. LOTTER.
